UNITED STATES PATENT OFFICE

161,109

PORTABLE GRASS TRIMMER

Bert F. Keiper, East Orange, N. J.

Application October 22, 1949, Serial No. 5,646

Term of patent 14 years

(Cl. D40—1)

To all whom it may concern:

Be it known that I, Bert F. Keiper, a citizen of the United States of America, and resident of East Orange, county of Essex, State of New Jersey, have invented a new, original, and ornamental Design for a Portable Grass Trimmer, of which the following is a specification, reference being had to the accompanying drawings, forming part thereof.

Figure 1 is a front elevation of a portable grass trimmer, showing my new design;

Figure 2 is a side elevation and Figure 3 is a rear elevation of the trimmer shown in Figure 1;

Figure 4 is a top plan view and Figure 5 is a bottom plan view of the trimmer as shown in the other figures.

The characteristic features of my design reside in the portion shown in full lines.

I claim:

The ornamental design for a portable grass trimmer, substantially as shown and described.

BERT F. KEIPER.
